DESIGN FOR A CURTAIN STRETCHER HOLDER OR SIMILAR ARTICLE

John Pearl, Detroit, Mich.

Application March 12, 1941, Serial No. 99,526

Term of patent 14 years

To all whom it may concern:

Be it known that I, John Pearl, a citizen of the United States and a resident of Detroit, in the county of Wayne and State of Michigan, have invented a new, original, and ornamental Design for a Curtain Stretcher Holder or Similar Article, of which the following is a specification, reference being had to the accompanying drawing, forming part thereof.

Fig. 1 is a perspective view of the curtain stretcher holder or similar article, showing my new design;

Fig. 2 is a front elevational view; and
Fig. 3 is an end view of the same.

I claim:

The ornamental design for a curtain stretcher holder or similar article substantially as shown.

JOHN PEARL.
